FACE LIFTING DEVICE

Adolph M. Brown, Beverly Hills, Calif.

Application August 2, 1957, Serial No. 676,034

1 Claim. (Cl. 128—76)

My invention relates to a new mechanical device for temporarily eliminating or minimizing facial senescence. My previous work in this field has resulted in U.S. Patents Nos. 2,575,204, 2,575,205, 2,575,206 and 2,619,084.

As discussed in the foregoing patents, it is well known that as a person ages, the facial skin becomes relatively loose and sometimes sags into folds, often creating wrinkles or creases commonly regarded as undesirable from the standpoint of appearance or from the standpoint of its indication of age. Prior to the disclosures of the aforementioned patents, women sometimes underwent surgical "face-lifting" to eliminate what is generally considered an undesirable evidence of increasing age. Such surgery was, of course, sometimes painful, often expensive and occasionally dangerous.

Along with advancing techniques in cosmetics and feminine beauty care, increased emphasis has been placed on youthful appearance, characterized by smooth facial skin tissue. This has become an especially important desideratum as women have increasingly occupied professional and business positions. While my prior inventions are adaptable to general use, the youthful appearance achieved by minimizing facial senescence is of particular importance in some special fields, such as theater and entertainment. Cosmetic applications, especially liquid astringents, have long been used to achieve a temporary contraction of the skin, but such a cosmetic effect is only temporary in nature.

The first three patents mentioned taught the use of a plurality of mechanical devices provided with spicules or spurs which would penetrate the epidermis and retract the skin to tightness, eliminating wrinkles. The last of the four patents above-mentioned disclosed a device which would accomplish this result without the use of skin penetration. The use of such mechanical devices is considerably more efficacious in achieving facial skin contraction than cosmetic techniques, inasmuch as the initial "set" of the skin continues until the retracting devices are removed whereas cosmetic applications, often with a highly volatile alcohol component, are evanescent and dissipate within a short period of time. Often such cosmetic expedients as "astringents" give only a sensation of tightness caused by a layer of gelatin or glue on the skin. This greater dependability of the devices and method taught in previous patents no doubt accounts for their commercial success.

The present invention is a further improvement over the previous devices. Its object is to provide a device for temporarily alleviating the effects of facial senescence which achieves all the advantage of my aforementioned inventions, including that the device eliminates penetration of the integument and any physical discomfort associated with such penetration; is simpler to apply; requires only a single tensioning or retracting member; is capable of adjustment without removal to a desired degree of tautness upon and after application; is capable of removal and reapplication (while relaxing the skin over

2

intervening periods such as overnight); requires only a single small application of adhesive material on either side of the head; is more readily concealed and retained in position once applied; and in some embodiments serves as an ornament of the hair.

Generally stated, the object of this invention is to provide, when applied, the same youthful appearance heretofore achieved by a surgical face lift. As will be readily understood this effect is achieved only while the device is worn and the effect is temporary.

These and other objects and advantages will appear from the specification and drawing hereof, and the device shown in the accompanying drawings is given as illustration of one preferred embodiment of the invention, while I claim the device as shown or claimed and all equivalents thereto.

Figs. 1-4 show steps of applying the invention;

Fig. 5 is a view of the anchor member hereinafter described; and

Fig. 6 is a perspective view of the resilient tensioning member with its associated comb element;

Fig. 7 is a plan view of the comb element alone.

The device is provided with an anchor element 3 in the form of an oval-shaped woven, open-mesh, cloth tab (shown in Fig. 5).

The anchor element may be provided with a tip portion 5 having an opening therein which may, if desired, be reinforced with a grommet or multiple mutually reinforcing layers. This tab may be secured to the skin with a small quantity of any of a number of well-known adhesive substances at a point near the temples, preferably inside the hairline.

While the shape of the anchor element 3 may vary, it has been found important to form this element of a porous material. A fabric of 80 or 90 mesh has been found suitable. The porosity of the material permits the adhesive liquid which is applied to the skin to migrate or flow through the openings, spread on the outer side, and to congeal there, fixing the anchoring element 3 in a securely bonded relation to the skin. If desired, the portion 4 of the anchoring element at the end thereof opposite the tip portion 5 may also be treated with the adhesive to embed the fabric in the adhesive for full attachment to the coated area of the skin. Suitable adhesives can be formulated of various synthetic and rubber-like adhesives capable of maintaining a strong bonding relation with the skin and should be relatively non-allergenic.

The device also comprises elongated resilient or elastic tensioning members 7 and an associated comb element 8.

The comb 8 (which may also serve as a buckling function, as hereinafter explained) is provided with two central slot portions 9, 10 arranged in parallel spaced relationship, divided by a narrow partition 10a, and spaced inwardly of the margins of the comb or buckling element 8. Both elastic tensioning members 7 in assembly may extend transversely through both slots 9, 10. The slots 9, 10 are dimensioned to have a sufficient width so as to permit the tensioning members 7 to be threaded therethrough in an endwise sliding movement, yet to embrace and retain the tensioning members 7 in place while the latter are under stress. The tensioning members 7 may, along part of their length, be disposed in a stacked or layered relation, as in Fig. 6, forming a loop portion 20 as they extend through the slots 9, 10 and about the partitioning rod 10a in such relationship. The tensioning members 7 themselves should be of a length less than the distance across the top of the head from one temple to the other but which can be stretched over the distance into engagement with the tabs constantly to urge the tabs and the skin to which it is secured in

the direction off of the face to withdraw loose skin from the face. Ordinarily, an elastic tensioning member which extends to between 10 to 14 inches under stress will be satisfactory. The positioning of the device across the crown of the head is desirable so that the device will in operation exert a pull or tension rearwardly as well as upwardly, tending to minimize not only horizontal folds or wrinkles in the face but also those substantially vertical therein.

The elastic tensioning member 19 may be provided at at least one of their extremities with hooks 15 or other engaging means adapted to be inserted into the openings 6 of the anchor members 3 or otherwise secured thereto. Other means of securing or engaging the anchor members 3 to or with the tensioning members may be employed.

When, as in Fig. 4 and more fully hereinafter described, the tensioning members 7 are engaged by the anchor members 3 and tensed therebetween, the tensioning members 7 are pulled into a snug hugging relationship with the walls of the slots 9, 10.

The loop portion 20 of the tensioning members 7 may be digitally raised from its snugly seated relationship in the slots and reduced in thickness by stretching so that either or both tensioning members 7 may slide therethrough to a shorter or longer extension as desired.

The comb-buckle member 8 may be positioned at or near the extremities of the tensioning members 7 which are opposite their other extremities adapted to engage the anchor members 3. This permits the buckle 8 to be positioned near the crown of the head where the buckle may be most readily concealed. Of course, if desired, the comb-buckle element 8 may be designed as an ornamental piece and exposed in the hair. Adjustment of the length of one tensioning member may be achieved by endwise sliding through the slots 9, 10 without disturbing the adjustment of the other.

Figs. 1-4 show the steps of applying the device. The user, as in Fig. 1, parts the hair in a line passing from one temple to another across the cranium. The hair on the side of the part forward on the head may be brushed upwardly and forwardly and on the rearward side of head, rearwardly and downwardly. The hair may be held in place by combs 1, 2 while the device is being applied.

Optimally, the anchoring tabs 3 should be affixed to the skin within an area of one inch square of the skin surface immediately anterior to or in front of the upper edge of the ear. This area is generally designated 30 in Fig. 1. The skin in this area, I have discovered in performing surgical face lifts, is thin and quite loosely attached to the underlying fascia and muscle. Such position of the tab 3 utilizes this physiological phenomenon most effectively to achieve the temporary alleviation of facial senescence.

After the user has applied the tabs adhesively as heretofore described, the hooks 9 are engaged in the openings 6 on their respective sides. The tension exerted by the elastic members is transmitted through the anchor members 3 and pulls or retracts the facial skin upwardly and rearwardly. By adjusting the extension of the tensioning members 7 by endwise sliding, as heretofore described, the user may achieve the degree of tension desired to eliminate or minimize the looseness or wrinkles in the facial skin and to provide maximum comfort. Fig. 4 shows the device as applied, with the tab 3 urged by the tensioning members 7 to a higher position on the head.

The comb 8 is provided with outwardly extending teeth portions 16 in spaced apart side by side relation along at least one of its margins. Optimally the comb 8 should rest upon the head near its crown, and the lengths permit this. By so dimensioning the lengths of the tensioning members 7 in relation to the comb member 8, the extension of either tensioning member 7 and consequently the strength of its tensioning effect upon the skin on its respective side of the face may be adjusted independent of the other.

The comb 8 is readily concealed after the device is applied merely by brushing or otherwise positioning the hair thereover. The tufts of hair are then embraced within the channels 17 between the comb teeth 16 and hold the device uniformly and securely in place, thus avoiding inadvertent displacement of the device or undesirable modification of the established tensioned relation and also minimizing any unsightly bunching of hair or inadvertent exposure of the device itself.

While the combination buckle-comb element has been deemed commercially most acceptable, modifications are possible, as by using one or more buckling elements together with one or more separate comb members. The buckling member may be any equivalent device which will permit the tensioning member to be held in position under stress under various degrees of tension.

Besides the functional advantages of this improvement over my earlier inventions, there are additional advantages, such as comparatively less cost in manufacture. Numerous changes may be made in the details of construction, arrangement, and operation, without departing from the spirit of the invention, especially as stated in the following claim.

I claim:

35 In a device for minimizing facial senescence wherein a liquid adhesive is applied directly to the skin for attachment thereto, a plurality of elongated resilient tensioning members dimensioned to have a normal length less than the distance between auditory members, a plurality of anchoring members consisting of an open mesh fabric portion adapted to enable penetration into the liquid adhesive applied to the skin for enabling the fabric to become embedded and become an integral part of the adhesive layer and another portion adapted to be connected to said tensioning members when stretched to urge said tensioning members in the direction towards each other and away from the face; a buckling member; said tensioning members having their other extremities opposite their points of connection to said anchor members engaged by said buckling member; said buckling member being adapted to permit endwise sliding of the tensioning members therethrough and having teeth extending laterally in side by side parallel relationship into engagement with the hair shafts for anchorage.
